DISPENSER FOR LINER-WOUND TAPE

Myron M. Hoover, Superior, Wis., assignor to
 Minnesota Mining & Manufacturing Company,
 St. Paul, Minn., a corporation of Delaware

Application December 6, 1941, Serial No. 421,856

2 Claims. (Cl. 242—56)

This invention relates to dispensers for lined or liner-wound tape, that is, tape that is wound in storage rolls with a liner. The liner is usually a strip of cloth, paper, Cellophane or the like, usually of the same width and approximately the same thickness as the tape. The liner and the tape are placed one on top of the other before being wound up into a roll so that the layers or convolutions of tape, when it is in roll form, are held apart and separated from each other by the liner. Liners are used in winding various kinds of tape whenever such separation is advantageous.

The invention finds particular utility in dispensers for tape that is "double-coated" (coated on both sides) with normally tacky or pressure-sensitive adhesive which is adherent without the necessity of activation by water, solvents or heat, such tape usually being covered with a liner on at least one side when wound in rolls and being removable therefrom without transfer or offsetting of the adhesive, due to the highly cohesive nature of the adhesive.

Such double-coated pressure-sensitive tape finds great utility as a substitute for a thin layer of liquid adhesive wherever two objects are to be adhered together, but one problem heretofore has been the handling of such tape during use. If one side of such tape is covered with a protective liner when it wound up in a roll for storage, the liner must be removed and disposed of in some way when the tape is unwound and severed into lengths for use. Heretofore such disposal has been time-consuming. It is highly desirable to eliminate this fault at little or no cost because one of the advantages of double-coated tape is that it saves time.

When using such double-coated liner-covered tape, if a length is severed with the liner still adhering to it the two layers must be peeled apart by hand at the cost of considerable time before actual use. If the liner is removed before severing, it must be drawn away from the tape and disposed of by an operation separate from the operation of withdrawing and severing the tape itself. If a dispenser is being used and a separate "take-up" roll is provided to receive and wind up the liner, such take-up roll must be either turned separately by hand or else an elaborate mechanism must be provided to vary the speed of the take-up roll to compensate for the roll's gradual increase in size as the liner is wound onto it.

Therefore, one of the objects of this invention is to provide a simple inexpensive tape dispenser;

which will dispose of a liner automatically; in which all the force or actuation that is required for disposal of the liner is supplied by the simple withdrawal of the tape from the supply roll, so as to adapt the disposal means to manual as well as to power-driven dispensers;

which will automatically dispose of a liner in such a manner that in manually operated machines the operator need do no more than to withdraw and sever the tape; and

in which the used liner is preserved for further use.

Dispensers embodying the principles of this invention have been highly successful in meeting fully all of the above requirements; whereas no device previous to this invention of which I know, has been found so to do.

According to the present invention a device is provided in a tape dispenser comprising a take-up roll rotatably mounted between the dispenser's tape supply roll and tape severing means in such a position that the lined side of the tape (that is, the side which is covered by the liner) contacts the take-up roll as the tape is drawn from the supply roll towards the severing means so that the moving tape rotates the take-up roll, thereby providing a rotating element around which the liner may be wound so as to remove it from the tape and dispose of it, i. e., take it off the tape and out of the way, as fast as the liner-covered tape is drawn past the take-up roll.

The take-up roll is rotated by its frictional contact with the moving tape. Friction between the tape and the take-up roll may be increased by passing the tape around an idler roller either before or after the tape contacts the take-up roll, thereby increasing the area of contact between the tape and the take-up roll. If the tape goes around the idler roller before it reaches the take-up roll, then the friction between the tape and the take-up roll may be still further increased by providing means for braking the idler roller. This requires a harder pull to draw the tape past the severing means with a subsequent greater tension and greater friction around the take-up roll.

The dispenser that is described and illustrated herein as an example of an embodiment of the present invention is a portable, manually operated dispenser for tape coated on both sides with pressure-sensitive adhesive which is wound up in a supply roll with a liner between each convolution of tape, such tape being separable from the liner without transfer or offsetting of the adhesive. Such a dispenser is suitable for use in

stores, factories, studios, libraries, laboratories, homes, etc.

In the accompany drawing:

Figure 1 is a left side elevation.

Figure 2 is a front elevation.

Figure 3 is a diagrammatic illustration of an alternative mode of operation.

Figure 4 is a diagrammatic illustration of a means for increasing friction between the tape and the take-up roll.

To the base 11 is attached the vertical framework 12 to which, in turn, are attached directly or indirectly various parts of the dispenser. Base 11 may be of heavy weight to prevent movement of the portable machine during use.

The supply roll R of double-coated (coated on both sides) pressure-sensitive adhesive tape is carried on the tape roll holder drum 13 which is rotatably mounted on the upwardly extending arm 12a at the rear of the dispenser and positioned or aligned so that when tape is withdrawn and threaded forwardly through the machine it will pass over the severing element at the front end.

Forwardly of the supply drum 13 the take-up roll 14 is rotatably mounted on the frame, its axis parallel with that of the drum 13 and aligned to contact the tape as it is threaded through the dispenser. A disc-shaped flange 14a on the right side of the roll serves as a guide during winding. A second flange or guide may be placed on the left of the roll if desired.

The take-up roll 14 is preferably located sufficiently below (or above) the line of travel which the tape would take were it stretched directly from the supply drum 13 to the severing means, so as to compel the tape to contact the take-up roll over a greater portion of its periphery than would result from a simple tangential contact, i. e., so as to compel the tape to pass somewhat around the take-up roll rather than to touch it at one point only. The take-up roll is rotated by means of the frictional contact between its periphery and the moving tape; the greater the area of contact between the two, the greater the friction and hence the desirability of having the tape contact the take-up roll along a substantial portion of its circumference.

To provide a means, when needed, for increasing the friction between the tape and the take-up roll, an idler roller 15 is rotatably mounted forwardly of and above the take-up roll 14 on the upwardly extending arm 12b in line to permit the tape to pass around its periphery.

When such a roller is to be contacted with the unlined pressure-sensitive adhesive coated side of the tape (as in the illustrated dispenser) the roller's periphery may be knurled and/or grooved so as to reduce the area of contact and thereby facilitate removal of the adhesive tape from it as the tape passes on towards the take-up roll.

The idler roller 15 may have a braking means such as the spiral spring 17 around the shaft 16 between the idler roller and the supporting arm 12b, the spring being loaded to press against the roller.

The idler roller 15 may be omitted from the machine, if desired.

A further optional means for increasing the friction between the lined tape and the take-up roll 14 may be in the form of a presser roller 18 (Figure 4) rotatably mounted on a horizontal shaft 19 whose other end may be pivotally mounted onto an upright bracket. The spring 20 be-

tween the base and the shaft is loaded to press the roller 18 upwardly against the take-up roll 14.

At the forward end of the dispenser there is attached to the base 11 the vertical support 21 at the top of which is attached the severing means comprising a severing edge 22 and a hard smooth shelf-like surface 22a immediately to the rear thereof onto which the leading end of the unsevered portion of the tape may be temporarily adhered to await the next dispensing operation. The severing means here shown is similar to that disclosed in Borden Patent No. 2,221,213 issued November 12, 1940.

In operation a roll of double-coated pressure-sensitive adhesive tape, wound with a liner between the convolutions thereof is mounted on the supply roll holder drum 13 and faced so that the tape leads off from the under side of the roll towards the front of the dispenser. The unwinding is begun in such a manner that the liner adheres to the upper side of the tape as it is led away from the roll, leaving the under side of the tape unlined with its adhesive surface exposed.

The tape T, thus covered or lined on its upper side with the liner L, is trained around the under side of the take-up roll 14 and is drawn forwardly. This forward movement of the lined tape with its liner contacting the periphery of the take-up roll 14, rotates the take-up roll counterclockwise (Figure 1). The tape and the liner are then separated and the unlined tape drawn forwardly. While the tape is being thus drawn forwardly, the liner is trained upwardly and rearwardly close around the periphery of the rotating take-up roll until its leading end is covered by the next convolution of lined tape as the latter comes from the supply roll and begins to contact the take-up roll. This first convolution of liner around the bare periphery of the take-up roll should be drawn tight and the turning of the roll should be continued until the leading end of the liner is sufficiently covered by the next convolution to hold the first convolution in place. At this point the forwardly advancing portion of the unlined tape T may be brought to rest by adhering its under side temporarily to the shelf-like surface 22a just to the rear of the severing element 22. This completes the threading and the dispenser is ready for operation.

To secure a piece of tape for use, the operator grasps the unlined tape just to the rear of where it is temporarily adhering to the shelf 22a, lifts it off from the shelf and draws it forwardly until the required length has passed beyond the severing edge 22 whereupon it is severed by drawing it downwardly against the edge. The severed portion is then ready for use. The forward end of the unsevered portion adheres temporarily to the shelf 22a in readiness for the next withdrawal.

This forward movement of the tape causes the take-up roll 14 to rotate counterclockwise at the necessary rate to take up the liner whereby the liner, its leading end being engaged between the lined tape and the take-up roll's periphery, as previously described, is drawn away from the tape and wound up around the take-up roll.

Sometimes, due to the kind or condition of adhesive or tape backing, or to atmospheric or to other conditions, it may be found that the liner L is not being wound up on the take-up roll 14 with sufficient tightness. For this or for other reasons, it may be found desirable to provide greater friction between the lined tape and the take-up roll, in which case the lined tape may first be led 75 from the supply roll R around the idler roller 15

and thence around the take-up roll, as shown by the dotted lines T' and L' in Figure 1.

This increases the friction because of the added area of the take-up roll's periphery which is contacted by the lined tape. The friction is further increased by the braking action that is exerted by the idler roller 15 on the tape which necessitates a harder pull by the operator with a resulting increased tension on the tape around the take-up roll. The braking action is brought about by the temporary adherence of the tape to the idler roller which latter is braked by the spring 17.

In handling some kinds of double-coated tape and/or due to some conditions or for other reasons, an alternative method of leading the tape from the supply roll R to the take-up roll 14 may be employed, as shown in Figure 3, which has frequently been found to be advantageous. The tape T, being coated with adhesive on both sides, adheres temporarily both to the liner above it and to the liner below it in the roll R. In threading a dispenser in the manner shown in Figure 3, the tape T and the liner L are separated from the roll R and from each other for several inches back from the leading end. The liner is unwound for nearly, but not quite, a full turn in advance of the tape so that the points x and y at which the liner and tape "break" away from the roll are separated by approximately the relative distance (or number of degrees) shown in Figure 3. The liner and the tape are then led away forwardly from the roll R, reunited to form two layers with the liner uppermost and then threaded through the dispenser from there on as previously described. Due to the adherence of the liner L to the tape which is beneath it on the roll R and the adherence of the tape T to the liner which is in turn, beneath it on the roll R, the points of "break" (x and y) will remain spaced apart approximately where they were first broken by hand in positions similar to those in the illustration.

In referring herein to the take-up roll 14, to the circumference and periphery thereof and contact therewith, etc., it is intended that the convolutions of liner that become wound upon it

be considered as a part of the roll. For example, reference to the friction between the advancing lined tape and the take-up roll means the friction between the lined tape and the outer convolution 5 of liner that is then on the roll.

Dispensers embodying this invention may employ power-driven means for drawing or propelling the tape through the machine and for severing and dispensing it, without departing from 10 the scope or spirit of the invention.

What I claim is:

1. A portable adhesive tape dispenser for dispensing double-coated pressure-sensitive adhesive tape wound in rolls with a removable liner, comprising a frame, a holder for a roll of such tape, a transverse passive severing element spaced therefrom at the front of the dispenser and adapted to sever the tape when tape is drawn downwardly against it after a desired length has been pulled from the dispenser and to hold by adhesive contact the remaining end in position to be grasped for pulling a further length from the dispenser when desired, and an interposed rotatable drum having its axis off a plane drawn 15 between the axis of the tape holder and the severing element, said drum being located to receive and wind up the liner as tape is withdrawn, the tape being in frictional engagement and automatically causing the drum to rotate at the necessary rate to take up the liner, whereby the withdrawal of tape automatically causes separation and winding up of the liner and the double-coated tape can be readily pulled out and severed 20 into desired lengths.
2. In the method of removing the liner from double-coated pressure-sensitive liner-wound adhesive tape by a take-up roll that is rotated by its frictional engagement with the tape when the latter is being withdrawn from a supply roll 25 thereof, the steps comprising separating the liner and the tape from each other as they leave the supply roll and reuniting them temporarily as they contact the take-up roll.
